EVAPORATING MEANS

Martin W. Baden, Winfield, Kans.

Application May 2, 1930. Serial No. 449,339

4 Claims. (Cl. 219—38)

This invention relates to an apparatus to be used in rapid evaporation of solutions, the object being to hasten the evaporation without the loss of salts or solid matter.

- 5 For this purpose the invention provides a means for setting a metal disc, with proper lugs on the underside, the said lugs are placed on top of the evaporating dish or container to be used in the process of evaporation.
- 10 With the above and other objects in view, the invention further includes the following novel features in detail of construction, to be herein-after more fully described, and illustrated in accompanying drawings and pointed out in appended claims.

15 The principal object of this invention is to place the Bunsen gas flame, or electric heater on top of the disc which is superimposed on top of the evaporating dish containing the solution to be evaporated instead of below which is the usual method used in laboratories. By so placing the heat on top of the solution excessive boiling over and spattering will not take place. The method will be just as effective insofar as loss 20 or contamination is concerned as if a water bath were used in evaporation of the aqueous or other solutions, and more rapid.

In the drawings:

Figure 1 is a side elevation of the improvement 30 in applied position in which a Bunsen burner is being used for heating the disc.

Figure 2 is a top plan view of the disc.

Figure 3 shows the construction in full of the disc.

35 Figure 4 is a side elevation of the improvement in applied position in which an electric heating element is used to heat the disc.

Figure 5 shows the construction of the electric heating element.

40 It will be noted as the description progresses that the laboratory equipment, which forms the subject matter of this invention, is to be used in place of the well known customary water bath. In the evaporating process of various aqueous

45 or volatile solutions which may contain several elements, salts or any solid matter, a water bath is used in many instances. The customary procedure is to place the evaporating dish or beaker in a water bath and evaporate the solution by the 50 slow means of boiling the water in the water bath.

My improvement consists of a disc 1 which is to be made in varying sizes to fit the numerous sizes of laboratory evaporating dishes or beakers; this disc is made of quartz, nickel or some

other metal or material which is rust resisting and non-corrosive.

The disc 1, as disclosed by the drawings is placed on top of the evaporating dish. The disc 1, at points adjacent to its periphery, is equidistantly provided with longitudinal and transverse lugs which are provided on the bottom side to provide the same with what I term lugs 3 and the inner corners of these lugs are notched to form the same with projecting fingers 4. The shoulders inward of the fingers 4 rest on the dish 2, while the fingers 4 contact with the outer periphery of the dish in such a manner that the disc is held firmly in place on the dish.

The disc 1 is approximately one-eighth inch 70 thick, but may be made thicker if so desired. The disc, as stated, is made of rust resisting or non-oxidizing material. As the disc becomes very hot it is impossible for the material to oxidize, as the steam or vapors that are evolved will not 75 come in contact with the disc due to the heat on the under side.

The disc 1 being arranged over the top of the dish which contains the solution to be evaporated in which embody the salts or solid matter of any 80 kind, as the case may be. The solution will be completely evaporated to a total solid without contamination or the loss by being spattered or boiled over as would be the case if the flame were put under the evaporating dish. In fact, the 85 effect of the disc with the heat on the upper side is similar to the direct rays of the sun or heat, and the evaporation by this method is very rapid and efficient.

The Bunsen gas burner may be used in evaporation or aqueous solutions where it is desired to evaporate the same to a "total solid". The electric plate is to be used as the source of heat where it is desired to evaporate volatile solutions.

A very novel feature of this apparatus is, volatile solutions may be evaporated with no danger of fires or explosions when the disc is used in conjunction with the electric plate.

The electric heater 5 is constructed with a 100 metal ring 6 on which insulating blocks 7 are placed, and a high resistance coil 8 of German silver, iron or some other high resisting metal is used for the heating elements. The resistance wires are connected to wire conductors and run 105 through insulating tubes to the electrical source. The metal ring is provided with a metal plate on top 9. The underside is left open so that the heat may be more efficiently transmitted to the disc 1.

Having described the invention, I claim:

1. Evaporating means comprising a disc, legs depending from the disc and shaped to engage the upper edge of a dish containing the fluid to be evaporated, and means above the disk for projecting heat rays downwardly through the disk.
2. Evaporating means comprising a dish to contain fluid to be evaporated, a disc arranged above the dish and spaced from the latter to provide a vapor outlet, legs for supporting the disc above the dish, and means above the disk for projecting heat rays downwardly through the disc into the dish.
3. Evaporating means comprising a dish to contain the substance to be evaporated, a disc

of heat conducting material positioned above and spaced from the dish to provide a vapor outlet, supporting legs for the disc provided with notches engaging the upper edge of the dish, and means for heating the disc from above.

4. Evaporating means comprising a dish to contain the substance to be evaporated, a disc positioned above and spaced from the dish to provide a vapor outlet, supporting legs for holding the disc above the dish, and an electric heating element positioned above the disc, the disc being open to permit heat rays from the electric heating element to project downwardly into the dish.
